UNITED STATES PATENT OFFICE

131,202

DESIGN FOR A HUMIDOR

James V. Vevirit, Lewiston, N. Y., assignor to McDonald Products Corporation, Buffalo, N. Y.

Application May 16, 1941, Serial No. 100,986

Term of patent 7 years

To all whom it may concern:

Be it known that I, James V. Vevirit, a citizen of the United States, residing at Lewiston, in the county of Niagara and State of New York, have invented a new, original, and ornamental Design for a Humidor, of which the following is a specification, reference being had to the accompanying drawing, forming part thereof.

The figure is a perspective view of the humidor showing the new design.

I claim:

The ornamental design for a humidor, as shown.

JAMES V. VEVIRIT.
